UNITED STATES PATENT OFFICE

143,541

DESIGN FOR A CASING FOR AN ELECTRIC HEATER WITH FAN

William E. Maxson, Jr., Chicago, Ill., assignor to
Chicago Electric Manufacturing Company,
Chicago, Ill., a corporation of Illinois

Application June 11, 1945, Serial No. 120,004

Term of patent 14 years

(Cl. D81—10)

To all whom it may concern:

Be it known that I, William E. Maxson, Jr., a citizen of the United States, residing at Chicago, Cook County, Illinois, have invented a new, original, and ornamental Design for a Casing for an Electric Heater with Fan, of which the following is a specification, reference being had to the accompanying drawing, forming a part thereof.

Figure 1 is a front view,

Figure 2 is a side view, and

Figure 3 is a top plan view of the casing for an electric heater with fan showing my new design.

The dominant features of my design reside in the portions shown in full lines.

I claim:

The ornamental design for a casing for an electric heater with fan, as shown and described.

WILLIAM E. MAXSON, JR.
